UNITED STATES PATENT OFFICE.

MARSHALL C. HARRIS, OF SAN FRANCISCO, CALIFORNIA.

SUCTION-DREDGER.

No. 797,109.

Specification of Letters Patent.

Patented Aug. 15, 1905.

Application filed November 25, 1904. Serial No. 234,275.

To all whom it may concern:

Be it known that I, MARSHALL C. HARRIS, a citizen of the United States, residing at 5 Market street, in the city of San Francisco, county of San Francisco, and State of California, have invented certain new and useful Improvements in Suction-Dredgers; and I do hereby declare the following to be a full, clear, and exact description of the said invention, such as will enable others skilled in the art to which it most nearly appertains to make, use, and practice the same.

This invention relates to improvements in suction-dredges, and more particularly to the cutter-head thereof; and it consists of the novel construction and arrangement of the parts.

Heretofore the cutter-head has been constructed in various ways, the more generally accepted type being a series of radial arms supporting a rotatable framework fixed upon the driving-shaft and having knife-blades riveted to the framework parallel with the axis of the driving-shaft.

The above-described construction is subject to various disadvantages, which it is the object of the present invention to eliminate by constructing a cutter-head that will displace the maximum of dirt with the minimum of power, break up the dirt into small particles, reduce the cost of operation and facilitate the making of repairs, and to cut a normally level floor in the path of the dredger.

In accomplishing the above objects the invention consists, broadly, of an integral casting having arms radiating from a center hub, said arms being set forward at a slight angle to the line of the driving-shaft and having a socket-head approximately parallel with the line of the driving-shaft and approximately at right angles to the said arms, whereby the lines of said socket-heads converge toward the axis of the driving-shaft forward of the cutter-head, the socket-heads being provided with a series of sockets, into which tapered teeth are driven tight. The cutter-head or cutting-wheel is fixed on the end of the driving-shaft by squaring said shaft and setting it into a square tapered hole in the hub of the cutter-head or by keying or any other suitable means.

The dredger consists of a barge upon which the motive power is installed and having a driving-shaft running forward and down below the water-level to the depth desired to be cut and being capable of a lateral action at any level. The suction-pipe is run down with

the driving-shaft to a point just behind the cutter-head, whereby the debris displaced by the cutter-head is sucked up and delivered from the barge to any desired point by means of hydraulic suction-pumps.

In the drawings, Figure 1 is a front elevation of a cutter-head constructed in accordance with this invention and set at the working angle. Fig. 2 is a plan from above in cross-section of the same.

In detail the construction consists of the hub A, capable of a fixed attachment to the end of the driving-shaft B. The arms A' radiate from the hub and carry the socket-heads A². These socket-heads are set on lines converging toward the axis of the driving-shaft, so that the lower socket-head will be level when the driving-shaft is at an average inclination. This leaves the floor of the cut on a level plane. The sockets A³ are set in line along the socket-heads, their depths being tangential to the periphery of the cutter-head, so the cutter-teeth A⁴ will be given clearance to bite into the dirt. The teeth A⁴ are provided with tapered shanks to fit the sockets and are wrapped with burlap and driven tightly into the sockets. The burlap prevents the teeth setting in the sockets with rust. The cutting-points of the teeth can be given any form best adapted to negotiate the kind of dirt that they may be working in—for instance, round points for gravel formation and chisel-points for clay and the like.

The construction is capable of variations to suit conditions without departing from the spirit of the invention. It is sometimes desirable to stagger the teeth—for instance, by leaving one or two teeth out of each series of sockets and filling the gap by placing the teeth in line with it in the next series, and so on. The lines of the socket-heads may be placed spirally across the line of the driving-shaft, so that the first teeth of the succeeding series take hold before the last teeth of the preceding series clear, so that the torque on the cutter-head may be constant. The cutter-head may be one integral piece of cast-steel, or it may be built up, as circumstances demand, the germ of the invention being the substitution of the series of teeth units for the continuous cutting edge. The advantages of this construction are manifold. The teeth break up the debris and better prepare it for the suction-pipe. Dirt formation refractory to the old form of cutters yields readily to the pointed attack of the teeth with the expendi-

ture of the same power. In the case of breakage a tooth is readily loosened and replaced.

Having thus described this invention, what is claimed, and desired to be secured by Letters Patent, is—

1. A cutter-head for suction-dredges, consisting of a hub; arms radiating therefrom; socket-heads on said arms approximately parallel with the line of the driving-shaft, and converging toward the axis thereof; teeth set in said socket-heads on lines tangential to the periphery of the cutter-head.

2. A cutter-head for suction-dredges consisting of a hub; arms radiating therefrom; socket-heads on said arms; teeth set in said socket-heads on lines tangential to the periphery of the cutter-head.

3. A cutter-head for suction-dredges consisting of a plurality of socket-heads, a series of teeth secured to each of said heads and set tangentially to the periphery of a rotatable body.

4. A cutter-head for suction-dredges comprising a rotatable body, a plurality of socket-heads at the periphery of said body, and a series of teeth secured in each of said sockets.

5. A cutter-head for suction-dredges comprising a hub, arms radiating therefrom, a socket-head at the outer end of each arm, and a series of teeth secured to each of said sockets.

6. A cutter-head for suction-dredges comprising a hub, arms radiating therefrom, a socket member at the outer end of each arm, and a series of teeth removably secured in each of said sockets.

7. A cutter-head for suction-dredges comprising a plurality of socket members, and a plurality of teeth secured to each of said socket members.

8. A cutter-head for suction-dredges comprising a plurality of socket members, and a plurality of teeth removably secured to each of said members.

9. A cutter-head for suction-dredges comprising a plurality of socket members, a plurality of sockets formed in each of said members, and teeth removably secured in said sockets.

10. A cutter-head for suction-dredges comprising a rotatable body, socket members at the periphery of said rotatable body, a plurality of sockets formed in each of said socket members, teeth removably secured in said sockets tangentially to said rotatable body.

In testimony whereof I have hereunto set my hand this 10th day of November, 1904.

MARSHALL C. HARRIS.
